UNITED STATES PATENT OFFICE.

WILLIAM W. BEVAN, OF MELROSE, MASSACHUSETTS.

DESIGN FOR A BONBON-SPOON.

No. 39,468.

Specification for Design.

Patented Sept. 1, 1908.

Application filed June 6, 1908. Serial No. 437,210. Term of patent 3½ years.

To all whom it may concern:

Be it known that I, WILLIAM W. BEVAN, a citizen of the United States, residing at 3 Wood avenue, Melrose, in the county of Middlesex and State of Massachusetts, have invented a new, original, and ornamental Design for a Bonbon-Spoon, of which the following is a specification, reference being had to the accompanying drawing, forming part thereof.

The figure is a plan view of a bon-bon spoon, showing my new design.

I claim:

The ornamental design for a bon-bon spoon, as shown.

WILLIAM W. BEVAN.
